UNITED STATES PATENT OFFICE.

FRIEDRIECH FETTE, OF COLLEGEVILLE, CALIFORNIA.

TRUSS.

SPECIFICATION forming part of Letters Patent No. 598,177, dated February 1, 1898.

Application filed August 24, 1897. Serial No. 649,297. (No model.)

To all whom it may concern:

Be it known that I, FRIEDRIECH FETTE, a citizen of the United States, residing at Collegeville, in the county of San Joaquin and State of California, have invented certain new and useful Improvements in Trusses; and I do declare the following to be a full, clear, and exact description of my invention, such as will enable others skilled in the art to which it appertains to make and use the same, reference being had to the accompanying drawings, and to the figures of reference marked thereon, which form a part of this specification.

My invention relates to certain new and useful improvements in trusses, such as will more effectually maintain the internal parts, which would otherwise protrude through a rupture, in a normal position at all times, and which may be cheaply constructed; and it consists in the peculiar construction, novel combination, and adaptation of parts herein-after described, and particularly pointed out in the claims hereunto annexed, reference being had to the accompanying drawings for a better comprehension hereof, in which—

Figure 1 is a plan view of my truss having the wire bent in position for application to the patient. Fig. 2 is a sectional view of the same with the wire straight. Fig. 3 is a plan view of the back of the stay-pad. Fig. 4 is a plan view of the back of the supporting-pad.

Similar figures of reference indicate corresponding parts in the several views.

1 represents a wire or rod of suitable stiffness, on each end of which a screw-thread is cut. The said wire is of sufficient pliability to enable the same to be bent, as shown in Fig. 1, and at the same time maintain sufficient stiffness to cause a pressure for the purpose hereinafter set forth.

On one end of the wire 1 a pad 2 is attached by means of a plate 3, which is rigidly attached thereto and provided with a lug 4, into which lug 4 the end of the wire 1 is adapted to be inserted, there being an opening and thread cut therein for that purpose. A supporting-pad 5 of suitable material has a plate 6 rigidly attached to the back side of the same by means of the screws 8. Such plate 6 has two lugs 7 rigidly attached thereto, which are inserted in recesses in the said pad 5,

and are provided with openings transversely therein, which have screw-threads cut in the same, into which openings the end of the wire 1 is inserted and maintained rigidly in any position desired by means of a set-screw 9, which is inserted in an opening in the plate 6 between the lugs 7 and adapted to impinge upon the said wire 1. Straps 10, having a suitable buckle or other suitable fastening, are attached to the wire 1 near the pads, such straps being for the purpose of assisting in maintaining the pads in proper position while in use on the body of the patient. A strap 11 is rigidly attached to the strap 10 near the pad 2, and such strap 11 has a suitable fastening or loop 12 adjustably attached to its loose end. The plate 6 is provided near its outer end with a hook or button 13, adapted to receive the said loop 12. The said strap 11 is adapted for extreme cases and is passed between the thighs from behind and the loop 12 engaged with the hook or button 13, whereupon the internal parts are prevented from oozing from the under side of the rupture into the scrotum. The wire 1 may be constructed of a straight piece and may be bent in the desired form to fit the location on the body where it is desired to apply the truss.

The mode of operating my improved truss is as follows: The wire is first bent to the desired form, and the straps 10 are suitably secured to the same. The pad 2 is then inserted on one end of said wire 1, said pad 2 being adapted to fit loosely thereon. The plate 6, having the lugs 7, is rigidly attached to the pad 5, and the loose end of the wire 1 is inserted in the said pad 5 and lugs 7, there being an opening in said pad therefor, and the set-screw 9 is inserted in the plate between the lugs 7 and impinged upon the said wire 1, thus maintaining the pad 5 in rigid position. As will be seen, the position of the pad 5 may be varied by loosening the set-screw 9, changing the position of the pad 5 either vertically or horizontally or both vertically and horizontally on the wire 1, and tightening the set-screw 9 again. The truss is then placed on the patient with the pad 5 in position over the affected part, such pad 5 having been adjusted by means of the set-screw 9 with relation to the locality of the affected parts, so as to attain the best result.

The pad 2 is then placed in position on the opposite side of the body of the patient for the purpose of maintaining the pad 5 against the affected part at all times by means of the tension of the wire 1. The straps 10 are passed and fastened around the opposite side of the body for the purpose of preventing the truss from slipping from its proper position. As the patient assumes different position the pad 2 will adapt itself to such position by reason of being flexible on the wire 1. The strap 11 is then passed between the thighs from behind and the loop 12 engaged with the hook or button 13 on the pad back of the plate 6. As will be seen, the lower side of the pad 5 is maintained rigidly against the walls of the affected part.

I am aware that trusses have been made which comprise a single wire with pads attached thereon, and therefore I do not claim those features broadly; but

What I do claim as new, and desire to secure by Letters Patent, is—

1. In a truss the combination with a suitable wire having screw-threads cut on either end thereof, a stay-pad flexibly inserted on one end of such wire, a supporting-pad having the plate 6 rigidly attached to the back of the same, the lugs 7 rigidly attached to the said plate 6 and inserted in the supporting-pad, such lugs 7 adapted to engage with the other end of the said wire and the set-screw 9 inserted in the plate 6 and adapted to impinge upon the said wire all arranged and operating substantially as shown and for the purposes specified.

2. In a truss of the class described the combination with a spring-wire having screw-threads cut on either end thereof, of an adjustable pad attached to one end of such wire, an adjusting-screw inserted in the back of such pad and adapted to impinge upon the said spring-wire, a stay-pad rigidly attached to a plate having a lug thereon which is provided with an opening therein into which opening the other end of the spring-wire is inserted, the supporting-straps 10, the strap 11 attached to one of the straps 10, the loop 12 and hook or button 13, all arranged and operating substantially as shown and for the purposes set forth.

3. A truss composed essentially of a wire which may be bent to any desired form and having screw-threads cut on one end on which an adaptable pad composed of the pad-body 5, the plate 6 rigidly attached thereto, the lugs 7 rigidly attached to such plate 6 and inserted in recesses in the pad-body, into which lugs the wire aforesaid, is inserted the set-screw 9 inserted in the plate 6 and adapted to impinge upon the said wire, a stay-pad flexibly inserted on the other end of the said wire, the supporting-straps 10, the strap 11 and its fastenings, all arranged and operating substantially as shown and described.

In testimony whereof I affix my signature in presence of two witnesses.

FRIEDRIECH FETTE.
